UNITED STATES PATENT OFFICE.

JOHN WILSON BROWN, JR., OF PHILADELPHIA, PENNSYLVANIA.

DESIGN FOR A COMBINED FEED-SCREW AND CUTTER.

SPECIFICATION forming part of Design No. 24,912, dated November 19, 1895.

Application filed October 17, 1895. Serial No. 566,014. Term of patent 14 years.

To all whom it may concern:

Be it known that I, JOHN WILSON BROWN, Jr., a citizen of the United States, residing in Philadelphia, Pennsylvania, have invented a certain new and useful Design for a Combined Feed-Screw and Cutter, of which the following is a specification.

My design for a combined feed-screw and cutter of a meat-chopping machine is fully illustrated in the accompanying drawings, in which—

Figure 1 is a side view illustrating my new design. Fig. 2 is a section on the line 2 2, Fig. 1. Fig. 3 is a section on the line 3 3, Fig. 1. Fig. 4 is a section on the line 4 4, Fig. 1. Fig. 5 is an end view looking in the direction of the arrow, Fig. 1.

The essential features of the design are the peculiar shape of the screw and the arrangement of the threads.

A is the body of the screw, having a disk b and a shank A' projecting beyond the disk.

Extending from the disk to the end b' of the screw is a continuous thread a, and extending from a point some distance beyond the disk 25 to the end b' is a second thread, and extending from the point x where the taper of the screw begins are two additional threads a² a³, extending to the end b'. The pitch of the main threads a a' is increased at the tapered 30 end d, as shown, so as to correspond with the threads a² a³.

I claim—

The design for a combined feed screw and cutter of a meat chopping machine as herein 35 described and shown in the accompanying drawings.

In testimony whereof I have signed my name to this specification in the presence of two subscribing witnesses.

JOHN WILSON BROWN, JR.
